UNITED STATES PATENT OFFICE.

JOHN SCHEMINGER, JR., OF PROVIDENCE, RHODE ISLAND.

CONTROLLED ROTARY OIL BURNER.

Application filed August 7, 1919. Serial No. 315,983.

To all whom it may concern:

Be it known that I, JOHN SCHEMINGER, Jr., a citizen of the United States, residing at Providence, in the county of Providence and State of Rhode Island, have invented certain new and useful Improvements in Thermally Controlled Rotary Oil Burners; and I do hereby declare the following to be a full, clear, and exact description of the invention, such as will enable others skilled in the art to which it appertains to make and use the same.

This invention relates to liquid fuel burners, and more particularly to rotary oil burners of the type shown and described in my pending application, Serial No. 274,175, filed January 31, 1919.

The objects of the invention are to provide simple and efficient means for effecting a thorough vaporization of the oil or other liquid fuel, and the commingling of the vapor with air for feeding the burner; to provide means for effecting a steady and uniform flow of the liquid fuel from a pump to the burner, and to prevent the disquieting effect and irregularity in the flow which are caused by the pulsations of the pump in apparatus of this kind as heretofore ordinarily constructed. Further objects are to provide means for lubricating the driving gearing and burner shaft bearings, and at the same time to produce a cooling effect thereon and prevent overheating and injury to the working parts of the burner by causing a circulation therethrough of the lubricating medium; also to provide means for heating the fuel in its passage to the burner, thereby obtaining more perfect combustion and permitting the use of crude oil instead of the more refined products; also to dispense with a gravity feed; and to provide means for maintaining a pilot light by the use of gas from a street main, instead of an oil-fed pilot light, and generally to improve the construction and increase the efficiency of burners of the type shown in my aforesaid application.

The invention will first be hereinafter more particularly described, with reference to the accompanying drawings, which are to be taken as a part of this specification, and then pointed out in the claims at the end of the description.

In said drawings.

Figure 1 is a perspective view of an apparatus embodying my invention as applied

to an ordinary domestic furnace, either hot water, hot air or steam;

Fig. 2 is a vertical sectional elevation of a broken away portion of the furnace, showing in side elevation my improved rotary oil burner and its operating and feeding mechanism applied thereto;

Fig. 3 is a plan view of the apparatus shown in Fig. 2; the furnace being shown in horizontal section.

Fig. 4 is a detail plan view of the pre-heating and feed pipe system;

Fig. 5 is an enlarged vertical sectional elevation of the burner, taken on the line 5—5 of Fig. 3.

Fig. 6 is an enlarged vertical sectional elevation of the pump and its priming chamber;

Fig. 7 is a vertical sectional elevation of the oil separating and settling chamber;

Fig. 8 is a detail sectional view of the vertical feed-pipe supporting base;

Fig. 9 is a fragmentary detail view, in side elevation, of a part of the oil feeding system, taken on the line 9—9 of Fig. 3;

Fig. 10 is a fragmentary detail view, in side elevation, of a portion of the oil feeding system taken on the line 10—10 of Fig. 9;

Fig. 11 is an enlarged side elevation partly in section, of the worm-gear and pump casing, and connected oil circulating pipes for cooling and lubricating the motor-driven gears and burner-shaft bearings;

Fig. 11^a is a plan view, partly in section, of the worm-gear and casing; the cover of the worm-gear chamber being removed; and Fig. 12 is a front view of a portion of the apparatus including a thermostat and electrical connections controlled thereby, for automatically starting and stopping the motor, also showing an oil supply tank independent of the main fuel supply and associated parts, for automatically controlling the supply of fuel to the burner and the pilot light when an oil-fed pilot light is used instead of a gas-fed pilot light.

Referring to said drawings, in which the same reference letters are used to denote corresponding parts in different views, the letter A may denote an ordinary domestic furnace, the letter B a hollow casting or standard supporting the burner head and having journaled therein a vertical hollow shaft, C, within which is secured a vertical feed pipe C¹; the burner being located in the

ash pit of the furnace. The shaft C has secured thereon at or near its upper end a spray-plate or atomizing device, which is preferably of the construction shown, 5 though other forms may be employed. The letter M denotes an electric motor for rotating the spray-plate or atomizer D through the medium of a horizontal shaft m , which is coupled to the motor shaft and has its outer 10 end journaled in suitable bearings, preferably annular ball bearings m^3 and m^4 within the casting B. Said shaft m carries a helical gear m^1 arranged within the hollow casting B, in mesh with a larger helical gear m^2 15 fixed on the shaft C for imparting motion thereto. Any suitable gears may be employed, but preferably the larger gear is constructed of fiber or composition to deaden sound. The vertical shaft C, as shown, is 20 journaled in annular ball bearings E and E¹, located at the upper end and base, respectively, of the hollow casting or standard B, as shown in Fig. 5 of the drawings. The vertical feed pipe C¹, through which oil is 25 supplied to the burner, has its lower end screwed into a feed-pipe supporting base or casting C², which is bolted or otherwise secured to the base of the hollow casting B, on the under side thereof. The feed-pipe supporting casting C² is formed or provided 30 with a pendant hub-like portion having an opening in one side thereof which is in communication with the lower end of the vertical feed pipe C¹, and in said opening is 35 screwed an interiorly threaded sleeve e, to receive the end of the oil feed-pipe C³. Within said pipe C³ is fitted a smaller pipe C⁴, of such size as to leave sufficient space between it and the pipe C³ for the passage 40 of oil through the larger pipe. The pipe C⁴ is extended up through the oil feed pipe C¹ and supports at its upper end a T-coupling or head piece F, having secured therein 45 downwardly curved pies or nozzles through which jets of vapor or gas may be directed and projected against opposite sides of a dome or inverted cup-like member G, fixed on the upper end of the feed-pipe C¹, while other jets are projected against the spray 50 plate or atomizer D on opposite sides of its center, for the purpose of supplying fuel to maintain a pilot light for starting the burner and to heat said dome and spray-plate so as to facilitate combustion when the burner is 55 set in operation. The casting B has mounted thereon an annular member B² which is formed or provided with a central cone B³ which terminates in a cylindrical portion B⁴ of sufficient size to surround the vertical 60 shaft and leave a space therearound for the admission of air entering underneath the member B², between which and the top of the standard B there are placed a series of washers of asbestos or other material suitably spaced to permit the entrance of air be- 65

tween adjacent washers and the two castings B and B², and the air thus admitted travels upwardly along the vertical shaft and is directed against the underside of the spray plate, as indicated by the arrows in Fig. 5, 70 for supporting combustion and also exerting a cooling effect on the upper shaft bearing E. The annular member B² serves as a drip pan to receive any oil that may escape from the burner and which may escape from the 75 drip pan through a waste-pipe b, Fig. 1. The member B² is outwardly flaring and has a flat annular marginal portion or surface b² adapted to support the inner circumferential portion of a wire mesh or other reticulated or screen-like metal plate, the outer edge of which bears against the inner wall of the furnace, and on said plate is placed a body of asbestos or other refractory material, which surrounds the burner head and 80 serves to confine the heat or flame above said plate and within the fire box of the furnace so as to prevent excessive heating of the lower portion of the furnace with consequent injury to the shaft bearings and driving 85 gearing housed in the casting B. Between the body of the refractory material and the inner wall of the furnace, or its water-leg A¹, is placed a corrugated sheet metal plate R, which forms a combustion chamber surrounding the head of the burner and provides air spaces between it and the furnace wall, whereby currents of air are caused to pass upwardly through the channels r, formed by the corrugations, whilst other currents are drawn in between annular spaced members B⁵ and B⁶ of the burner head, by the suction created by the rotating spray plate, and passing downwardly between said members B⁵ and B⁶ are caused to pass up 90 underneath and through the spray plate for commingling with the vaporized oil in the manner indicated by the arrows in Figs. 2 and 5. The plate R also shields the water-leg A¹ of the furnace and prevents the accumulation of carbon or other products of combustion thereon, which must be forcibly removed from time to time, with liability to injure the furnace wall, whereas any such 95 accumulations on the protecting plate can be gotten rid of by removing the plate and substituting a new one at very little expense. The annular members B⁵ and B⁶ are flared outwardly at or toward their upper ends and the member B⁵ has its lower edge cut away 100 to fit over the fuel pipe p¹ where said pipe enters the burner and the two parts B² and B⁵ are rigidly secured together so as to prevent disconnection thereof, or independent movement one upon the other, by fastening 105 bolts or other means. The member B⁵ has inwardly extending lugs b³ adapted to support the superposed annular member B⁶, the outwardly flaring part of which is spaced 110 from the flaring portion of the member B⁵ 115

120

125

130

so as to provide a passage between the two members for the entrance of air which is drawn up underneath the spray plate, as indicated by the arrows in Fig. 5. The interior of the hollow casting or standard B forms an oil chamber in which are housed the helical gears m^1 and m^2 , and for the purpose of lubricating said gears by submerging them in oil and also the worm gears in the gear chamber H, and to produce a cooling effect of the oil it is caused to circulate through said chambers and the vertical shaft bearings, and to this end, the chamber H has secured thereto or formed thereon the casing of a rotary pump I which is used for drawing oil by suction from the worm gear chamber H and forcing it through a pipe h into the upper vertical shaft bearing E, from which it flows into and fills the gear chamber within the hollow standard or casting B, and from the latter chamber sufficient oil flows into the lower vertical shaft bearing E¹ to keep it submerged in oil. From the oil-filled gear chamber within the standard B, oil is drawn by the pump I through a pipe h¹ back into the worm gear chamber H, whereby a constant flow of oil into and out of the gear chambers and through the vertical shaft bearings is maintained, and by the circulation of the oil the worm and helical gears and vertical shaft bearings are thoroughly lubricated and at the same time a cooling effect is produced which prevents over-heating of the shaft bearings and driving gears. To prevent undue pressure of accumulated air within the gear chamber of the vertical hollow shaft C an air vent c¹ is formed in said shaft above the ball bearing E, through which air may escape, and ascending up the shaft will pass into the cavity of the dome G, and thence to the burner, with commingled vapor or gas. The worm-gear chamber H is provided with a gage h² to indicate the level of the oil therein, and with an oil cup h³ having a removable cover for filling the chamber with oil.

To feed the burner, I preferably provide an oil circulating system with means for heating the oil or other liquid fuel during its passage to the burner, together with means for separating a portion of the oil and the air contained therein from the major portion and causing the separated portion to flow quietly, continuously and evenly to the burner, unaffected by the pulsations or irregular movements of the pump piston or pistons, while the major portion is caused to ascend to a predetermined point so as to create sufficient back pressure opposed to and tending to counteract the pressure of the pump to accomplish the desired separation and quieting of the minor portion of the fuel. To this end a pump P is connected by a pipe p with an oil tank or other source of liquid fuel supply (not shown), and a pipe

p^1 leads therefrom to the separating and quieting device or separator K. The pipe p^1 is formed or provided with one or more coils p^2 therein, which surrounds the cone B³, or the cylindrical extension B⁴ thereof, below the burner head, and with a return bend p^3 which is connected with the inlet to the separator K; the purpose of said coils being to utilize the heat generated by the burner for heating the liquid fuel in its passage to the burner so as to facilitate vaporization and combustion. The pump P, of the form shown, is of ordinary construction and the intake port thereof is connected with a priming chamber P¹, which in this instance, as shown, is of globular form, and contains a strainer P². The priming chamber P¹ has secured thereon a removable cap P³ which serves also to clamp the upper flanged end of the strainer P² between it and the top of the chamber, in order that upon removal of the cap the strainer may be taken out for cleansing or other purposes, or a new strainer may be substituted therefor and secured in place by replacing the cap. The cap P³ has secured thereon the threaded end of an elbow which is coupled to the fuel feed pipe p. The casing of the separator K is preferably diamond shaped and arranged so that one of its reduced end portions is at the base thereof, which the pipe p^3 enters at one side while the other reduced end has an interiorly threaded discharge opening therein in which is screwed a coupling device on one end of a discharge pipe K¹, having on its other end a coupling member adapted for connection with an upwardly extended pipe K², and also having a check valve k therein to prevent back flow. The pipe K² is provided with an upward extension K³ which terminates in a return bend arranged to discharge into the mouth or funnel on the inlet end of a downwardly extending pipe K⁴ through which the liquid fuel discharged therein is conducted back to the supply tank or reservoir (not shown). The pipe section K³ is adapted to be turned part way around to bring its goose-neck end or return bend into position to discharge into a pilot light fuel supply tank L, (Fig. 23) for a purpose hereinafter explained. The break in the pipe connection between the adjacent ends of the pipes K³ and K⁴ is to prevent siphonic action after the pump is stopped tending to empty the pipe K² and thus prevent the maintenance of a solid column of liquid for exerting back pressure sufficient to insure a steady and uniform feed of fuel oil on again starting the pump.

At the base of the settling chamber K¹ of the separator there is a discharge opening K² with which is connected the pipe C³ which communicates with the vertical feed pipe C¹ for supplying fuel to the burner, as hereinbefore stated. In the pipe C³

is placed a check valve c^2 to prevent back flow of fuel oil, a regulating valve c^3 , by which the quantity of oil passing through the pipe may be increased or diminished 5 as desired, and a needle or plunger valve c^4 for automatically cutting off the fuel supply when the temperature of the furnace rises above a predetermined point. For this purpose a lever N is fulcrumed on a post 10 rising from the base casting of the burner and has its short arm arranged to press upon the stem c^6 of the plunger valve while its longer arm is connected by a cord or chain n with one arm of a lever N^1 fulcrumed 15 on a diaphragm O mounted on the furnace. The free end of the lever N^1 carries a counterbalancing weight N^2 . The diaphragm O is in communication with the water circulating system or steam space at the top of 20 the furnace, in order that when the heat of the furnace rises above the desired temperature the diaphragm will be expanded by the entrance of hot water, hot air or steam therein, thereby actuating the valve operating 25 lever and through it and the lever N depressing the plunger valve so as to cut off the supply of fuel to the burner. As the temperature is lowered the plunger valve will be opened by a spring acting thereon as 30 usual in this class of devices. To prevent injury to the valve c^4 by excessive pressure of the lever N on its stem, a stop c^7 is placed beside the valve in position to limit the downward movement of the depressing 35 lever. Mounted upon a T-coupling in the pipe C^3 there is a cut-off valve c^5 adapted for connection with the lower end of a pipe L^1 leading from the tank L when it is desired to connect the fuel tank with the pipe 40 for feeding oil instead of gas to maintain a pilot light. In order to supply gas to maintain a pilot light, the fuel feed pipe C^5 is provided with a T-coupling C^5 through which the gas feed pipe C^4 passes and has 45 its outer end brazed or otherwise secured within the depending end of an elbow c^8 which is connected by a union coupling member with a gas pipe C^6 (Figs. 3, 9 and 10) which is adapted to be connected with 50 the ordinary gas supply pipe or means for supplying gas to the building in which the burner is installed; said gas pipe C^6 being furnished with a cut-off valve c^9 for turning on or cutting off the pilot light gas supply. 55

It is desirable to utilize the same motor that rotates the vertical shaft of the burner and the spray plate thereon for driving both the fuel supply pump and the lubricating 60 pump, and to accomplish this, I couple the motor shaft to a shaft S , which carries the worm S^1 , which is housed in the worm-gear casing H ; said worm S^1 being in mesh with a worm gear carried by a shaft T that projects through and has its bearings in the

casing H and is operatively connected with one of the pistons of the lubricating pump for actuating the same; said shaft T being also operatively connected with one of the pistons of the fuel supply pump, for actuating the latter in unison with the lubricating pump. For convenience in assembling and to compensate for any difference in the alinement of said shafts, I provide a flexible coupling S^2 between the motor shaft 70 and said worm shaft, and also a flexible coupling T^2 between said worm gear shaft and the driving shaft T^1 of the fuel oil pump. (Figs. 2, 3, and 11a).

The means employed for automatically controlling the circuit of the electric motor by which rotary movement is imparted to the burner, whereby the burner is put into or out of operation in accordance with temperature changes influenced by the burner, 80 may be of any suitable construction, but preferably substantially the same as shown in my application above mentioned, and in Patent No. 1,388,541 granted Homer C. Woodbury, August 23, 1921, with certain 85 changes resulting from the use of a gas-fed pilot light with provision for using an oil fed pilot light and the introduction of other novel features hereinafter described.

The circuit controlling mechanism (not 90 shown) is enclosed in a box U , (Fig. 12), in electrical connection with the thermostat T and also in electrical connection with a tank-float control switch, for automatically starting and stopping the motor and controlling the supply of fuel to the burner and the pilot light, when an oil-fed pilot light is used instead of the gas-fed pilot light. It will be seen that oil is fed to the burner from a source of supply (not shown) 100 by means of the force pump and co-operating devices hereinbefore described, while gas is fed to the pilot light, instead of feeding both the burner and the pilot light from a common source, but oil may be used to feed the pilot light from a supply tank independent of the main fuel supply, and for feeding both the burner and pilot light with oil by gravity flow from an auxiliary oil feed tank, the tank and tank-float control 105 switch and circuit connections shown in Fig. 12 are brought into action.

The box U may contain an electro-magnetic relay and circuit wires for connection with a battery (not shown) and the thermostat T , for making and breaking the electric circuit in response to changes of temperature, causing its pointer t to swing into contact with the contact point t^1 or the point t^2 , as usual in thermally controlled apparatus. When it is desired to use oil for feeding the pilot light, the electric circuits being connected with the float-controlled electric switch, oil may be fed by gravity from the tank L to the pilot light through the 110 115 120 125 130

pipe C^3 which, for the time being, is connected with the pipe L^1 , by opening the cut-off valves l and c^6 , in said pipe L^1 , said tank being supplied with oil by turning the 5 pipe section K^3 , (Figs. 1 and 12), partly around, so that it will discharge into the tank L instead of discharging into the return pipe K^4 as hereinbefore described. The tank L is provided with an overflow 10 pipe L^2 through which oil in excess of that necessary to feed the pilot light is conducted back to the main source of supply or storage tank to prevent waste, and in order that the tank L may be emptied, if desired, a by-path is provided from the pipe L^1 to the 15 pipe L^2 through a connecting pipe L^3 having a cut-off valve l^7 therein controlling the passage of oil therethrough. In order to keep the pilot light burning at times when 20 the motor is idle and the furnace fire out, when the pilot light is being fed from the tank L , the stem W of the tank-float is passed loosely through the free end of a switch lever Y and has secured thereon, on 25 opposite sides of said lever, tappets w and w^1 , whereby when the oil in the tank is exhausted the switch lever will be shifted by the descending float into contact with the contact point y , thereby closing an electric 30 circuit through the battery and the relay magnet and thus effecting a closure of the motor circuit and starting the motor, so as to replenish the oil in the tank. When the tank is being filled, as the liquid rises there- 35 in the lower tappet w , on its upward movement, will raise the switch lever into contact with the contact point y^1 , thereby again closing the electric circuit through the battery and relay magnet, thus breaking the 40 motor circuit and stopping the motor. These operations are automatically repeated from time to time as it becomes necessary to replenish the oil in the tank, so that sufficient oil may be kept therein to keep the 45 pilot light burning continuously, for automatically relighting the burner when the main fuel supply is turned on, without requiring the services of an attendant for this purpose. 50 It will be understood of course that the specific atomizing device and the fuel oil separator and the rotary oil pump with its priming chamber, which are especially designed and adapted for use as elements of 55 the complete combination or apparatus embodying my invention, are nevertheless merely preferred forms of such devices for accomplishing the desired results, and that other forms may be substituted therefor 60 without departing from the spirit and scope of my invention, and these specific devices are not specifically claimed herein.

The spray plate or atomizer is preferably constructed of sheet steel, swaged or pressed 65 into concavo-convex form, and provided

with a series of apertures or openings therethrough which are formed by slitting the metal plate at intervals, preferably along circular lines, and bending the metal upwardly on one side of the slit, as at d , and 70 downwardly on the other side thereof, as at d^1 , so that the openings are oval in form and have their axes extending in a plane at an angle to the periphery of the plate. The central portion of the plate has secured 75 thereto, by rivets or otherwise, a central sleeve or hub-like portion D^1 which has an annular flange on which are formed or secured a series of upright or upwardly extending blades d^2 , which extend at an angle 80 to the axes of the oval openings and are designed to break up and whirl the oil or liquid fuel outwardly for commingling with the air passing up through the plate. The margin or periphery of the plate is slit 85 radially and the adjacent metal is bent upwardly and downwardly on opposite sides of the slits so as to form vane-like portions or blades d^3 . As the spray plate is rotated in the direction of the arrows (Fig. 3), the air entering the burner from below the plate is raised by the depressed portions d^4 of the metal surrounding the openings and forced upwardly by the raised portions d and whirled outwardly, and is also thrown upwardly and outwardly by the upwardly inclined blades d^3 , so as to effect a thorough 90 atomization of the oil and the commingling of the vapor with air.

Having thus described my invention, what 100 I claim as new and desire to secure by Letters Patent is:

1. In a rotary oil burner, oil feeding means comprising a supply tank, a circulating system including a pump for drawing 105 the oil from the tank, and means for separating the oil and returning the larger portion to the tank while the lesser portion is caused to pass quietly and evenly to the burner unaffected by the pulsations of the 110 pump.

2. In combination with a rotary oil burner, a liquid fuel supply tank and devices for feeding the burner from said tank including a pump and means whereby the liquid fuel 115 is drawn from said tank by the pump and a portion thereof separated and freed from air and caused to flow quietly and evenly to the burner while the major portion is caused to ascend to a predetermined point from 120 which it is conducted back to said tank; the ascending column of liquid being adapted to exert back pressure acting on the lesser portion to effect the passage of the latter to the burner unaffected by the pulsations of the 125 pump.

3. In a rotary oil burner, oil feeding means comprising a supply tank, a circulating system including a pump and means for separating the oil and causing the larger 130

portion to return to the tank while the lesser portion is caused to pass quietly and evenly to the burner unaffected by the pulsations of the pump, together with means for heating the lesser portion in its passage to the burner.

4. In a rotary oil burner, an oil circulating system including a supply tank, a feed pipe, a pumping and a separating device between the burner and pump whereby the oil drawn from the tank is divided into unequal portions and the larger portion caused to move in an ascending column to a predetermined point and then return to the tank, the ascending column being adapted to exert back pressure acting on the smaller portion and with the aid of the pump causing said smaller portion to pass quietly and evenly to the burner unaffected by the pulsations of the pump.

5. In a rotary oil burner, a hollow vertical shaft carrying a spray plate having openings therein for the passage of air therethrough, means for rotating said shaft, an oil feed pipe extending up through said hollow shaft and carrying an inverted cup-like member arranged centrally over said spray plate, and a gas feed pipe extending up through said oil feed pipe and having a nozzle thereon arranged over said cup-like member for directing jets of vapor or gas against the same.

6. In a rotary oil burner, a hollow vertical shaft carrying a spray plate having openings therein for the passage of air therethrough, means for rotating said shaft, an oil feed pipe extending up through said shaft and having an inverted cup-like member thereon arranged centrally over said spray plate, and a gas feed pipe extending up through said oil feed pipe and having secured thereon downwardly curved pipes or nozzles for directing jets of vapor or gas against said cup-like member and against the spray plate on opposite sides of its center.

7. In a rotary oil burner having a rotating atomizing device and means for rotating said device, an oil feed pipe and a supply tank for feeding the burner, a gas pipe for feeding a pilot light, and an oil feed pipe enclosing the gas pipe and adapted for connection with an oil supply tank for feeding the pilot light when the gas-fed pilot light is not used.

8. In a rotary oil burner, a hollow vertical shaft carrying a spray plate having openings therein for the passage of air therethrough, an oil feed pipe extending through said shaft above said spray plate and having means thereon for spreading the oil over the surface of said spray plate, a standard in which said shaft is journaled, a pan mounted on said standard and having an outwardly flaring portion and a cen-

trally arranged substantially conical portion to provide an air passage upwardly between it and said shaft, and a plurality of outwardly flaring rings mounted on said pan, the flaring portions of said rings being slightly separated to permit air to be drawn downwardly therebetween and commingled with air passing upwardly through said conical portion.

9. In a rotary oil burner, a hollow standard, a vertical hollow shaft carrying at its upper end a spray plate, having openings therein for the passage of air therethrough, said shaft being journaled in bearings arranged within said standard, a pan mounted on said standard having an outwardly flaring portion and a centrally upwardly extending disposed substantially conical portion surrounding said shaft and spaced therefrom to provide an air passage therethrough for discharging air under said spray plate, and a plurality of flaring rings above said pan arranged one above another and separated to permit the passage of air therebetween.

10. In a rotary oil burner, a hollow standard, a vertical shaft journaled in ball bearings within an oil chamber formed in said standard, an atomizing device on said shaft, and means for submerging said bearings in oil, together with means for forcing oil into said chamber and causing it to flow therefrom, thus effecting a circulation of the oil through or around said bearings and the shaft driving mechanism so as to produce a cooling effect thereon.

11. In combination with a rotary oil burner located in the ash pit of a furnace, a body of refractory material surrounding the burner head, and a corrugated metal plate interposed between said refractory material and the inner wall of the furnace, said plate serving to protect the inner wall of the furnace and the corrugations therein serving as air ducts.

12. In combination with a rotary oil burner placed within the ash pit of a furnace, a corrugated furnace wall protecting plate supported between the burner and the inner wall of the furnace, the corrugations in said plate serving as ducts for the upward passage of air.

13. In combination with a rotary oil burner placed within the ash pit of a furnace, a corrugated furnace wall protecting plate supported between the burner and the inner wall of the furnace, the corrugations in said plate serving as ducts for the upward passage of air, together with a rotating atomizing device adapted to create suction tending to draw the air entering said ducts downwardly underneath said plate for commingling with vaporized oil.

14. In combination with a rotary oil burner having a rotating spray plate, said

plate having circular series of openings therethrough and associated means for creating suction and drawing up inwardly moving currents of air, a corrugated annulus surrounding the burner head adjacent the inner wall of the furnace, the corrugations of said annulus forming air ducts, and said spray plate operating to induce currents of air entering said ducts and passing underneath and through the openings in the spray plate.

15. The combination, in a rotary oil burner, of a vertical shaft having a rotating spray plate or atomizer thereon, said plate having openings therein for the passage of air therethrough, a standard in which said shaft has its bearings, an oil feeding device, a drip pan mounted on said standard and having a hub-like portion surrounding said shaft so as to provide an air passage between it and the shaft, provision being made for the admission of air between said standard and pan, and a plurality of outwardly flaring rings mounted

25 on said drip pan and slightly separated to provide for the passage of air therebetween.

16. The combination, in a rotary oil burner, of a vertical hollow shaft having a rotating spray plate or atomizer thereon, said plate having openings therein for the passage of air therethrough, a standard in which said shaft has its bearings, an oil feed pipe extending up through said hollow shaft, and a plurality of outwardly

35 flaring rings mounted on said standard, the flaring portions of said rings being slightly separated to provide for the passage of air therebetween, and an air passage being provided from below said rings upwardly

40 around the vertical shaft.

17. The combination, in a rotary oil burner, of a vertical shaft having a rotating spray plate thereon, said spray plate having series of openings therein for the passage of air therethrough, a standard in which said shaft is journaled, a drip pan on said standard having a central cylindrical member surrounding said shaft so as to provide an air passage between it and the

50 shaft, air ducts being provided between said

pan and the top of said standard leading into said passage, and concentric outwardly flaring rings mounted on said drip pan and having the flaring portions thereof slightly separated for the passage of air therebetween, whereby air is drawn inwardly and upwardly between said standard and drip pan and between said concentric rings and caused to pass underneath the spray plate and upwardly through said openings.

18. In a rotary oil burner, a standard, a vertical hollow shaft journaled in said standard, an oil feed pipe in said hollow shaft, a drip pan mounted on said standard and having a central portion of conical form extending upwardly around said shaft, an outwardly flaring ring mounted on said drip pan, and a second outwardly flaring ring mounted on the first named ring also flaring outwardly; the flaring portions on said rings being spaced apart to permit the admission of air therebetween.

19. The combination in a rotary oil burner of a vertical hollow shaft having a spray plate thereon, means for rotating said spray plate, an oil feed pipe extending through said shaft, a dome-like oil spreader and distributor at the discharge end of said pipe, a gas feed pipe extending through said oil feed pipe for feeding a pilot light, and means on said gas feed pipe facing the convex surface of said dome for directing a jet or jets of gas against said surface.

20. The combination in a rotary oil burner of a vertical hollow shaft having a spray plate thereon, means for rotating said spray plate, an oil feed pipe extending through said shaft, and carrying at its upper end a dome-like oil spreader and distributor, a gas feed pipe extending through said oil feed pipe, and downwardly curved pipes or nozzles at the upper end of said gas pipe for directing jets of gas against said dome and spray plate.

In testimony whereof I affix my signature in the presence of two witnesses.

JOHN SCHEMINGER, JR.

Witnesses:

B. M. OFFUTT,

THOMAS F. BURKE.
